UNITED STATES PATENT OFFICE.

BERRY A. BAXTER, OF MANSFIELD, OHIO.

STOVE-DOOR.

944,475.

Specification of Letters Patent. Patented Dec. 28, 1909.

Application filed June 15, 1909. Serial No. 502,386.

To all whom it may concern:

Be it known that I, BERRY A. BAXTER, a citizen of the United States of America, residing at Mansfield, in the county of Rich-
5 land and State of Ohio, have invented cer-
tain new and useful Improvements in Stove-
Doors, of which the following is a speci-
fication.

My invention relates to improvements in
10 stove doors.

One of the objects of my improvement is
to provide means of retaining a stove door
in a closed position by the weight of the
15 parts of the operating mechanism and also
to hold the door in place when it reaches
its full open position.

Another object is to provide a cheap and
efficient means of retaining the door in its
closed and full open positions.

20 I attain these and other objects by the
mechanism illustrated in the accompanying
drawing in which:

Figure 1 is a vertical section of my de-
vice showing it applied to a stove door with
25 the door and retaining mechanism in full
open position. Fig. 2 is a vertical section
of Fig. 1 showing the door with the retain-
ing or locking mechanism in closed posi-
30 tion. Fig. 3 is a plan view of the counter-
weight showing depressions in the surface
to permit of the ends of the links to be piv-
oted below the surface. Fig. 4 is a plan
35 view of the opposite side of the counter-
weight shown in Fig. 3 showing depressions
into which one end of a connecting bar is
attached. Fig. 5 is a side or edge view of
40 Figs. 3 and 4. Fig. 6 is a plan view of a
yoke shaped connecting bar. Fig. 7 is a
plan view of one of the links. Fig. 8 is an
edge or side view of one of the links show-
45 ing the off-set bends. Fig. 9 is a horizontal
sectional view of the device showing the
counter-weight in contact with the oven-
wall to maintain the door in open position.

50 In the drawing, reference numeral 1 re-
presents the oven of a stove and 2 one of the
side walls. Links 3 are pivotally secured
to the side walls of the oven by the pins 4
and 6. Connecting bars 7 preferably made
55 in the form of a yoke as shown in Fig. 6
are pivotally connected to the door and the
free ends *a* and *b* are secured to a weight
8 by the screws 9 and 10 and it is further
prevented from longitudinal movement by
the notches 11 formed in the ends of the con-

necting bar which engage the rib 12 which
crosses the grooved portions 13 of the coun-
ter-weight.

Depressions 14 and 15 are provided in the
counter-weight 8 and one end of the links
is pivotally attached to the counter-weight
as shown in Figs. 1 and 2 by the pins 16
and 17. The depressions 14 and 15 are pro-
60 vided in the counter-weights for the purpose
of permitting the ends of the links 3 to
pivot freely below the surface of said coun-
ter-weights to operate in close proximity to
the side walls of the oven. Although two
65 depressions, designated 14 and 15, are pro-
vided, as shown in Fig. 2, it is obvious that
only the lower one is used when the door
mechanism is assembled and the links con-
70 nected to the counterweights. The purpose
of providing two depressions is to permit
75 the use of the same counterweights on either
the right or left side of the oven wall. This
arrangement pivotally connects the door
18 to the counter-weight 8 which is in turn
70 pivotally connected to the side walls of the
oven as described. The door is hinged to
the walls of the oven in the usual manner.

The operation of my device is as follows:
When the door is being closed, the counter-
weight with its operating mechanism is
85 forced to travel toward the back or rear wall
of the oven, transcribing an arc on the ra-
dius of the links 3 until it assumes the posi-
tion shown in Fig. 2. When the links 3 and
80 connecting bar or bars 7 are parallel with
each other, the door is in close proximity to
its closed position and the weight of the
parts becomes effective to keep the door
closed. When, however, the links and con-
90 necting bar or bars of the door are at an
inclination to the plane of the oven, as
shown in Fig. 2, the counter-weight with its
operating mechanism securely holds the door
95 in close contact with the walls of the oven
as they pass over the center of the axis of
the pivotal connection and have a tendency
100 to movably lock the door in closed position.

The counter-weight and the operating
mechanism serve to offset the weight of the
105 door and retain it in its closed position.
When the door is being opened, the links
and weight are forced to travel in a for-
ward direction toward the front of the oven,
transcribing an arc on the radius of the
110 links in the opposite direction from that of
closing until they assume the position shown
in Fig. 1, which shows the door in full open

position forming a shelf level with the bottom of the oven. The counter-weights are drawn forward by the connecting bar or bars and they strike the front walls *a a* of 5 the stove thereby retaining the door in the position shown in Figs. 1 and 9.

The above arrangement describes a cheap and effective means of retaining a stove door in closed and open positions.

10 Having fully described my invention, what I claim and desire to secure by Letters Patent is:

15 1. In a stove, a hinged door, links pivotally connected to the walls of the stove at one end, counter-weights pivotally secured to said links, connecting bars pivotally connected to the door and rigidly connected to the counter-weights.

20 2. In a stove, a hinged door, links pivotally connected to the walls of the stove at one end, counter-weights pivotally secured to said links, a yoke-shaped connecting bar pivotally connected to the door and rigidly connected to said counter-weights.

25 3. In a stove, a hinged door, a link pivotally secured to said stove, a counter-weight pivotally secured to said link, a connecting bar pivotally secured to said door and rigidly connected to said weight whereby the 30 door is maintained in a closed or open position.

35 4. In a stove, the combination of an oven

and a hinged door; of counter-weights; connecting bars pivotally secured to said door and rigidly secured to said counter-weights, 35 links pivotally secured to the side walls of the oven and to said counter-weights whereby the counter-weights and operating mechanism serve to keep the door in close contact with the walls of the oven as described. 40

5. In a stove provided with a hinged door, a bar pivotally connected to said door, a weight secured to the free end of said bar, a link pivotally connected to the walls of the stove and to said weight, said weight 45 being adapted to contact with the walls of the stove and maintain the door in open position.

6. In a stove provided with a hinged door, a bar pivotally secured to said door, a link 50 pivotally secured to said stove, a weight pivotally connected to the free end of the link and rigidly secured to said bar, said link, bar and weight coöperating to maintain the door in closed position under tension and to maintain the door in full open position by contact of the weight with the walls of the stove as described and set forth. 55

In testimony whereof I affix my signature in presence of two witnesses.

BERRY A. BAXTER.
